Patented Mar. 23, 1976

239,335

BAKERY TRAY OR THE LIKE

Lewis T. Johnson, Bartlesville, Okla., assignor to Phillips
Petroleum Company, Bartlesville, Okla.

Filed Dec. 26, 1973, Ser. No. 428,426

Term of patent 14 years

Int. Cl. D3—02

U.S. Cl. D87—1 R

F/G. 2

FIG. 3

FIG. 4

FIG. 5

FIG. 6

FIG. 1 is a top perspective view, with one corner partially in section, of a bakery tray or the like showing my new design, the corner shown partially in section is like the other corners;

FIG. 2 is a top plan view;

FIG. 3 is a side elevation view;

FIG. 4 is an end elevational view;

FIG. 5 is an enlarged sectional view taken on the line 5—5 of FIG. 2;

FIG. 6 is a bottom plan view showing one-half of the tray, the other one-half being identical to that shown.

I claim:

The ornamental design for a bakery tray or the like, as shown and described.
